UNITED STATES PATENT OFFICE.

KARL FR. HUMMEL, OF GOTTLIEBEN, SWITZERLAND.

VENEERING-PRESS.

No. 921,253.

Specification of Letters Patent.

Patented May 11, 1909.

Application filed October 15, 1908. Serial No. 457,873.

To all whom it may concern:

Be it known that I, KARL FR. HUMMEL, a citizen of Switzerland, and resident of Gottlieben, Thurgau, Switzerland, have invented 5 certain new and useful Improvements in and Relating to Veneering-Presses, of which the following is a specification.

The object of my present invention relates to a veneering press in which one of the press 10 plates *e. g.* the upper one is pressed by means of a regulator spindle against a number of plates the action of which can be partly disengaged.

In the accompanying drawing in which I 15 have illustrated my invention like letters of reference refer to like parts of the different views.

In said drawings:—Figure 1 shows a side view of the press, Fig. 2 shows a front view 20 of Fig. 1, Fig. 3 shows a plan-view on line A—B of Fig. 1.

The lower plate *b* is firmly mounted in an iron frame *a*. Above the plate *b* I arrange a movable plate *c* which is connected to a 25 spindle *d* by means of which the plate *c* can be moved up and down in a well known manner. The connection between the movable plate *c* and spindle *d* is made by two supports *e* carrying on the lower flange a number *e. g.* 30 eight flat springs *f₁*—*f₈*. The plate *c* is supported by two spindles *g₁*—*g₂* which are mounted in flat rails *q₁*—*q₂* forming bearings for said spindles and placed across the supports *e*. By means of said spindles *g₁* *g₂* the 35 plate *c* can be suitably drawn toward the supports *e* and the springs *f₁*—*f₈*. By this motion the springs are caused to rest against supports *h₁*—*h₈* mounted upon the upper plate *c* to which they transfer their elasticity. 40 If a smaller wooden plate is to be veneered the same is laid upon the center of the lower press plate *b*. In this case it is superfluous to engage the outer pairs of springs *f₁*, *f₂*, *f₇*, *f₈*.

It is for this reason that I arrange next to each of the inner four supports *h₃*—*h₆* a flat 45 rail *i₃*—*i₆* which are connected by two rails *k₁* and *k₂*. These rails are mounted in cross-grooves of the supports *h₃*—*h₆* and connected by a flat rail *m*. Connected to the rail *m* is an arm *m₁* guided in a groove of the support 50 *h₈* and pivotally connected to a lever *o* pivotally fastened by the pivot *p* to the support *h₈*. By moving inward the lever *o* the slide formed by the parts *i₃*—*i₆*, *k₁*, *k₂*, *m*, *m₁* is pushed so far inside that the rails *i₃*—*i₆* 55 come to rest upon the supports *h₃*—*h₆*. The plate *c* is now moved toward the spindles *g₁*—*g₂* whereby the springs *f₃*—*f₆* are at once engaged while the pairs of the outer springs *f₁*, *f₂*, *f₇*, *f₈* only approach their respective 60 supports *h₁*, *h₂*, *h₇*, *h₈* and are disengaged by the inward motion of said lever *o*.

The single features of my device can of course be changed within the limit of my 65 invention.

What I claim as new and desire to secure by a United States Letters Patent, is:—

In a veneering press the combination of a movable press plate (*c*) acting under the influence of springs, a movable slide consisting 70 of two rails (*k₁* and *k₂*) of a cross bar (*m*) of an arm (*m₁*), a pivotally mounted lever (*o*) connecting to said slide, four cross-bars (*i₃*—*i₆*) mounted across said slide, and adapted to engage the four inner pairs of springs 75 (*f₃*—*f₆*) and to disengage the two outer pairs of springs (*f₁*, *f₂*, *f₇*, *f₈*) if the said lever is moved inward, substantially as described and for the purpose set forth.

In testimony whereof I have hereunto 80 signed my name this 29th day of July 1908, in the presence of two subscribing witnesses.

KARL FR. HUMMEL.
